UNITED STATES PATENT OFFICE.

FRANK A. IHRCKE AND CYRUS A. PARTENHEIMER, OF CHICAGO, ILLINOIS, ASSIGNEES
TO GEO. S. JOHNSTON COMPANY, OF CHICAGO, ILLINOIS, A CORPORATION OF ILLINOIS.

GOOGLES AND THE LIKE.

Application filed January 10, 1921. Serial No. 436,173.

To all whom it may concern:

Be it known that we, FRANK A. IHRCKE and CYRUS A. PARTENHEIMER, both citizens of the United States, and both residing at 5 Chicago, in the county of Cook and State of Illinois, have invented certain new and useful Improvements in Goggles and the like, of which the following is a specification.

10 The present invention has to do with certain improvements in goggles. The features of the invention are well adapted for use in connection with goggles for industrial purposes; but it will presently appear 15 that the features of the invention are not limited to this or other classes of service. Nevertheless, since the features of the invention are very well adapted for use with industrial goggles, we have illustrated and 20 will describe their use in this connection.

In many cases, and especially in connection with goggles for industrial use, the crystals of the goggles become pitted or otherwise injured so that they can no longer 25 be clearly seen through. It therefore becomes desirable to replace the crystals so as to correct this deficiency without the necessity of throwing away the entire goggles themselves. One of the objects of 30 the present invention is to provide a new and simple form of removable mounting for the crystals so that the crystals can be removed or replaced in a very simple manner and without the necessity of using special tools.

Another object of the invention is to provide a goggle construction in which the frames may be made of metal instead of from fiber or other composition material 40 as has been customary in the past. In this connection another object is to provide a construction of frame which can be very readily stamped out from sheet metal or from metal tubing by simple die processes.

45 Another object of the invention is to provide a removable mounting for the crystals which may be made entirely of metal, and which will also serve as a convenient attachment for the nose or bridge piece.

50 Other objects and uses of the invention will appear from a detailed description of the same which consists in the features of construction and combination of parts hereinafter described and claimed.

In the drawing:

55 Figure 1 shows a front face view of a pair of goggles embodying the features of the present invention;

Fig. 2 shows a bottom view corresponding 60 to Fig. 1;

Fig. 3 shows a section taken on the line 3—3 of Fig. 1 looking in the direction of the arrows;

Fig. 4 shows a section taken on the line 4—4 of Fig. 1 looking in the direction of 65 the arrows;

Fig. 5 shows a detailed face view of one of the crystal holding rings; and

Fig. 6 shows a view at right angles to 70 Fig. 5.

The goggles illustrated in the drawing include two frame members 10 and 11 of similar construction joined together by a flexible bridge piece 12. The frame members are provided with straps 13 and 14 which 75 reach around the back of the head of the wearer in the usual manner.

Each of the frame members or guards 10 and 11 is of generally cylindrical form having a flush front edge 15 and having its rear edge 16 curved to conform in a general way to the face of the wearer. These guards are conveniently pressed or stamped out of sheet metal tubing such as aluminum or thin gauge steel. Furthermore each guard 80 is preferably provided with a series of vent openings 17, and when these openings are provided they may be formed by stamping or pressing the ears 18 outwardly during the same operation in which the guards 85 themselves are formed. It will be observed that the rear portion of each guard is shown as being deflected outwardly as compared to its front end so as to better conform to the contour of the face of the wearer. This 90 enlargement is readily produced during the pressing or stamping operation. It is thus possible to completely form the guard from a section of sheet metal tubing at one operation which not only produces the vent 95 openings and ears but also gives the guard the desired contour. The rear edge of each guard may be covered so as to avoid injury to the face of the wearer. This may be done in any suitable manner as by placing 100 a strip of split tubing of rubber or the like 19 over the edge, sewing or stitching the same to the guard at a number of points 105 20.

For this purpose the metal guard may be punched at each of the points 20 during the same operation as that in which it is formed. The inner ends of the straps 13 and 14 5 may serve to hold the working strips in place at the points where said inner ends are passed through the slots 21 in the guard.

Each guard is provided with a removable crystal 22. These crystals are preferably of 10 circular form although in those cases in which the guards are non-circular the crystals may also be made of similar contour.

A crystal carrier 23 is provided for each 15 crystal; each crystal carrier is of the same contour as the crystal which it carries; and its outer peripheral portion is beveled as clearly illustrated so as to securely grip the edge of the crystal. The inner portion of each crystal carrier is formed as a neck 20 adapted to seat snugly within the corresponding guard when in working position. Each crystal carrier is preferably cut at a convenient point so that the crystal can be inserted or removed from it by spreading 25 open as shown in Fig. 5; but the parts are so proportioned that when the neck is seated into the guard the carrier will be retained against such expansion and the crystal will therefore be prevented from coming out 30 of it.

At one point, generally adjacent to the split, the crystal carrier is provided with an ear 24. When the crystal carrier is set into place in the guard, this ear passes through 35 a slot in the inner side of the guard as clearly shown in Fig. 4; and the ear then serves as a convenient element to which is attached the bridge piece 12. The crystal carrier thus serves not only the function of supporting the crystal, but also of providing an 40 attachment for the bridge piece.

The opposite side of the crystal carrier may be secured within the guard in any suitable manner as by means of a spring catch 45 25 secured to the inner face of the guard and engaging a slot 26 in the crystal carrier.

While we have herein shown and described 50 only a single embodiment of our invention, still we do not limit ourselves to said embodiment except as we may do so in the claims.

We claim:

1. A pair of goggles comprising in combination a pair of cylindrical eye guards 55 each comprising a section of metal tubing having its inner edge shaped to conform generally to the contour of the face of the wearer and having its outer edge lying at right angles to its axis, a strip of protecting 60 material laid over said inner edge, stitches securing the same to the guard and passing through perforations in the metal of the

guard, a crystal carrier for each guard, each crystal carrier being of split circular form and having its outer portion recessed for the 65 accommodation of the edge of a crystal and having its inner portion of cylindrical form and adapted to seat snugly into the outer end portion of the guard, there being a slotted 70 perforation at the inner side of each guard adjacent to the position of the crystal carrier, a lug on the crystal carrier passing through said slotted perforation, a bridge piece joining together the lugs of the two crystal carriers and independent locking 75 means for securing each crystal carrier within the corresponding guard at a point opposite to its lug, substantially as described.

2. A pair of goggles comprising in combination a pair of cylindrical eye guards 80 each comprising a section of metal tubing having its inner edge shaped to conform generally to the contour of the face of the wearer and having its outer edge lying at right angles to its axis, a crystal carrier for 85 each guard, each crystal carrier being of split circular form and having its outer portion recessed for the accommodation of the edge of a crystal and having its inner portion of cylindrical form and adapted to seat 90 snugly into the outer end portion of the guard, there being a perforation at the inner side of each guard adjacent to the position of the crystal carrier, a lug on the crystal carrier passing through said perforation, a 95 bridge piece joining together the lugs of the two crystal carriers and independent locking means for securing each crystal carrier within the corresponding guard at a point opposite to its lug, substantially as de- 100 scribed.

3. A pair of goggles comprising in combination a pair of cylindrical eye guards each comprising a section of metal tubing having its inner edge shaped to conform gen- 105 erally to the contour of the face of the wearer and having its outer edge lying at right angles to its axis, a crystal carrier for each guard, each crystal carrier being of split circular form and having its outer por- 110 tion adapted for the accommodation of the edge of a crystal and having its inner portion of cylindrical form and adapted to seat snugly into the outer end portions of the guard, there being perforations at the inner 115 side of each guard adjacent to the position of the crystal carrier, a lug on each crystal carrier passing through its perforation, a bridge piece joining together the lugs of the two crystal carriers, substantially as de- 120 scribed.

FRANK A. IHRCKE.

CYRUS A. PARTENHEIMER.
